(57) **CLAIM**

The ornamental design for an electronic display for a wearable device with graphical user interface, as shown and described.

DESCRIPTION

FIG. 1 is a front view of an electronic display for a wearable device with graphical user interface, showing our new design;

FIG. 2 is an enlarged front view thereof, the graphical user interface is shown separately for clarify of illustration;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken line showing of an electronic display for a wearable device in FIGS. 1, 3-7 forms no part of the claimed design. The broken line showing of portions of the graphical user interface in FIGS. 1 and 2 forms no part of the claimed design.

1 Claim, 7 Drawing Sheets
